(57) CLAIM

The ornamental design for a hockey jersey, as shown and described.

DESCRIPTION

FIG. 1 is a frontal elevational view of a Hockey Jersey, showing my new design; and,

FIG. 2 is a rear elevational view thereof.

The broken line showing of text within the chest patch of FIG. 1 is for illustrative purposes only and forms no part of the claimed design.

1 Claim, 1 Drawing Sheet
